US0D1100200S

(12) **United States Design Patent** (10) **Patent No.:** **US D1,100,200 S**
(45) **Date of Patent:** **** Oct. 28, 2025**

(54) **IMPLANTABLE ARTIFICIAL BRONCHUS**

(71) Applicant: **Pulmair Medical, Inc.**, San Diego, CA (US)

(72) Inventors: **Marcelo G Lima**, Del Mar, CA (US); **Murilo Pundek Rocha**, São Paulo (BR); **Herbert Radisch, Jr.**, San Diego, CA (US)

(73) Assignee: **Pulmair Medical, Inc.**, San Diego, CA (US)

(**) Term: **15 Years**

(21) Appl. No.: **29/938,097**

(22) Filed: **Apr. 18, 2024**

Related U.S. Application Data

(63) Continuation of application No. 29/836,450, filed on Apr. 27, 2022, which is a continuation of application No. 29/757,073, filed on Nov. 3, 2020, now Pat. No. Des. 954,953.

(57) **CLAIM**

The ornamental design for an implantable artificial bronchus as shown and described.

DESCRIPTION

FIG. 1 is a perspective view of an implantable artificial bronchus showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the implantable artificial bronchus that form no part of the claimed design.

1 Claim, 4 Drawing Sheets
